UNITED STATES PATENT OFFICE.

BENNY M. SWANSON, OF LOS ANGELES, CALIFORNIA.

COMBINATION ANGLE TABLE.

Application filed June 20, 1921. Serial No. 478,969.

To all whom it may concern:

Be it known that I, BENNY M. SWANSON, a citizen of the United States, residing at Los Angeles, in the county of Los Angeles 5 and State of California, have invented new and useful Improvements in Combination Angle Tables, of which the following is a specification.

My invention relates generally to work 10 supporting structures and more particularly to an adjustable angle table that is adapted to be positioned on the bed plate or table of a shaper or like machine for engaging and supporting work that is to have an angular 15 surface or cut made upon its upper face, or in which holes are to be drilled at predetermined angles.

The principal objects of my invention are to generally improve upon and simplify the 20 construction of the existing types of similar work holding devices, to provide a device that is relatively simple in structure, capable of being easily and cheaply produced, readily manipulated when adjusting 25 the engaged work, and further, to provide an angularly adjustable work holder that will be very effective in performing its intended functions.

With the foregoing and other objects in 30 view, my invention consists in certain novel features of construction and arrangement of parts that will be hereinafter more fully described and claimed, and illustrated in the accompanying drawings, which shows one 35 specific embodiment, in which:

Fig. 1 is a top plan view of an angularly adjustable work holding block or table of my improved construction with parts thereof broken away and in section, in order to 40 more clearly illustrate the construction of the device.

Fig. 2 is a side elevational view of the adjustable block or table, the same being positioned on the table or bed plate of a shaper, 45 and with parts of the device in section.

Fig. 3 is a detail section taken approximately on the line 3—3 of Fig. 1.

Referring by numerals to the accompanying drawings, which illustrate a practical 50 embodiment of my invention, 10 designates the main body portion of the lower member of the work supporting block or table, said body being in the form of a disc 10 and the

lower portion thereof terminating in a flange 11 that is adapted to rest directly upon and be secured to the table or bed plate 12 of a shaper or like machine.

In order that the disc or base member 10 may be adjustably positioned on the table 12, the base flange 11 may be provided with 60 arcuate slots such as 11^a and which receive bolts 12^a, the latter passing through the shaper table and being retained therein by suitable nuts 12^b.

Formed in the upper portion of the body 65 10 of the base member is an annular groove 13 that is inclined with respect to a horizontal plane, and the flange 14 or that portion of the body immediately above said inclined annular groove, and which is slightly smaller in diameter than the diameter of the main body portion of the base member 10, has an inclined upper surface 15 that is parallel with the inclined annular groove 13.

The upper member of the device comprises 70 75 a disc-like body 16 the diameter of which equals the diameter of body 10, and formed integral with the upper portion of said body 16, is a flange 17 the diameter of which is substantially equal to the diameter of base 80 flange 11 of the lower member.

Formed in the lower portion of the body 85 16 is an annular groove 18 which, when the parts of the device are in their normal positions, occupies an inclined plane that is oppositely arranged with respect to the plane occupied by the groove 13, and that portion of the body of the upper member 16 below said inclined groove 18, constitutes a flange 19 the underface 20 of which is inclined so 90 that it occupies a plane parallel with that occupied by said groove 18.

In the form shown, the upper member of 95 the device comprises also a work receiving or work supporting surface 23, shown as separate from the block 16.

In the embodiment shown I have formed in flange 17 a pair of oppositely arranged arcuate slots 21, and passing therethrough and through suitably located apertures in a 100 work supporting plate or table 23 are bolts 24, the upper ends thereof carrying nuts 25 that occupy countersunk recesses 26 that are formed in the top of the plate or table 23.

By virtue of the construction just described, the work receiving plate or table 23

may be rotated upon the upper block 16 and firmly locked to said block after such rotative adjustment.

Formed in the plate or table 23 is a series 5 of radially disposed slots 27 that are substantially of inverted T shape in cross section in order that they may receive the heads and lower portions of the shanks of bolts 28, and which latter may be utilized for 10 directly engaging the work positioned on the plate or table 23 or as attaching and anchoring means for work engaging straps or clamps (not shown).

Interposed between the bodies of the blocks 15 10 and 16 is a disc 29 having inclined upper and lower faces that are adapted to bear against the correspondingly inclined faces 20 and 15 on blocks 16 and 10, said interposed disc being formed in mating halves in 20 order to facilitate the assembling or taking apart of the device, and the line of division A between the mating parts being disposed so that portions 30 of the parts of said interposed disc overlap or extend past each other 25 at the center of the device.

Formed integral with the marginal portion of disc 29 and on the top and bottom thereof, are flanges 31 that overlie the flanges 14 and 19 on the bodies 16 and 10, and extending inwardly from the outer portions of these flanges 31, are annular flanges 32 that occupy inclined planes corresponding to the planes occupied by the upper and lower faces of the interposed disc 29, and said annular 35 flanges occupy the grooves 13 and 18 that are formed in discs 10 and 16. (See Fig. 3.)

Formed in the edge of the disc 29 and in alignment with the overlapping portions 30 of the parts of said disc, is a substantially rectangular recess 33 in which is arranged a block 34, and said block is provided on its inner face with substantially rectangular notches 35 that are adapted to receive the flanges 14 and 19 on the discs 10 45 and 16.

Passing through aligned apertures formed in block 34, the parts of disc 29 and the overlapping inner portions 30 of said parts, is a rod 36 one end of which is screw seated 50 in the edge portion of the interposed disc 29, at a point diametrically opposite said block 34.

The end portion of this rod that projects outwardly from the block 34 receives a tubular member 37, and which latter is locked on the projecting portion of the rod by a nut 38 that is mounted on the threaded end portion of said rod.

By tightening this nut 38, the tubular 60 member or sleeve 37 bears against the outer surface of block 34 and causes the same to bear against the flanges 14 and 19 of the members 10 and 16, thereby effectively locking the latter against relative rotary movement after the member 16 has been adjusted

to an angular position relative to the lower or base member.

In the use of my improved work supporting block, the work that is to be provided with an inclined cut in its upper face or 70 which is to be drilled to form inclined or angular holes, is positioned on top of disc 23 and firmly clamped thereupon by the bolts 28 or clamping members carried thereby, after which the nut 38 is unscrewed in order 75 to relieve the clamping pressure of the inner end of sleeve 37 against block 34 and consequently permitting the intermediate disc 29 to be freely rotated upon the lower member 10, and likewise to permit the upper member 80 16 to be independently rotated upon disc 29.

By manually engaging sleeve 37, which performs the function of a handle, intermediate disc 29 can be rotated in either direction upon base member 10, thereby 85 changing the position of the angular plane occupied by the top of said intermediate disc and correspondingly changing the angular plane occupied by the top of upper member 16 and the work carrying plate 23 90 that is positioned thereupon.

Further adjustment of the member 16 may be accomplished by rotating the same upon the inclined upper surface of the intermediate disk, and after the upper portion of the work supported on the table 23 has been brought into a true horizontal plane the parts of the device are locked in their adjusted positions by tightening the nut 38 on the projecting end of rod 36 and 100 which action, through sleeve 37, clamps the block 34 against the flanges 14 and 19 of members 10 and 16, and also clamps the intermediate disc against rotation by the arrangement of said block 34 within the 105 recess 33.

Thus, the upper surface of the work is positioned in a true horizontal plane and in such position said work may be engaged by the tool of the shaper or machine upon 110 which the device is positioned, and when said work is removed from the holder, the cut or surface engaged by the tool will have the desired angle relative to that portion of the work that was positioned directly against 115 the upper surface of disc 23.

In order to accurately determine the degree of adjustment imparted to the member 16 and the work supporting disc or table carried thereby, suitable guide marks may 120 be located at corresponding points on the peripheral surfaces of the bodies of the members 10 and 16 and a suitable graduated scale may be arranged on the peripheral surface of disc 29, and by observing the 125 positions of the graduations on the intermediate disc with respect to the fixed marks on the members 10 and 16, a very accurate adjustment of the work carrying member 130 can be accomplished.

A work supporting table or block of my improved construction is comparatively simple, is capable of being easily and cheaply produced, may be advantageously used wherever certain pieces of work require the formation of angular cuts or faces, or the boring of holes at predetermined angles, and said device is capable of ready adjustment and is very effective in performing its intended functions.

It will be readily understood that minor changes in the size, form, number and construction of the various parts of my improved work supporting block or table may be made and substituted for those herein shown and described without departing from the spirit of my invention, the scope of which is set forth in the appended claims.

I claim as my invention:

1. An angular adjustable work supporting table comprising a relatively stationary base having an inclined upper surface, an upper member carrying a slotted work receiving surface and having an inclined lower face, means on said work receiving surface for engaging and clamping work positioned thereupon, an intermediate member mounted for rotation between said base and upper member, said intermediate member having inclined upper and lower faces, and said intermediate member and said base and upper member having interengaging parts.

2. An angularly adjustable work supporting table comprising a relatively stationary base having an inclined upper surface, an upper member carrying a slotted work and receiving surface and having an inclined lower face, means on said work-receiving surface for engaging and clamping work positioned thereupon, an intermediate member mounted for rotation between said base and upper member, said intermediate member having inclined upper and lower faces, and said intermediate member and said base and upper member having interengaging parts, and means for locking said upper member and intermediate member against rotary movement relative to each other and relative to said base.

3. In a device of the class described, a relatively fixed base having an inclined top surface, a member mounted for rotary movement on the inclined top surface of said base, said member having inclined top and bottom surfaces, an upper member supported by said rotatably mounted member and having an inclined bottom surface that cooperates with the inclined top surface of

said rotatably mounted member, and a work receiving plate adjustably arranged on said upper member.

4. In a device of the class described, a relatively fixed base having an inclined top surface, a member mounted for rotary movement on the inclined top surface of said base, said member having inclined top and bottom surfaces, an upper member supported by said rotatably mounted member and having an inclined bottom surface that cooperates with the inclined top surface of said rotatably mounted member, a work receiving plate adjustably arranged on said upper member, and means for locking said rotatably mounted member and said upper member against relative rotary movement and against rotary movement upon said base.

5. In a work supporting block comprising a base provided with an inclined upper surface, an upper member, an intermediate member supporting said upper member and having an inclined lower surface, and a locking block on the outside of said intermediate member and cooperating with means extending therethrough to clamp said locking block against said base member and said upper member.

6. In a work supporting block comprising a base provided with an inclined upper surface, an upper member, an intermediate member supporting said upper member and having an inclined lower surface, and a locking block on the outside of said intermediate member and cooperating with means extending therethrough to clamp said locking block against said base member and said upper member, said locking block being engaged by a sleeve surrounding said means and adapted to serve as a handle.

7. In a work supporting block comprising a bottom member and an upper member, an intermediate member adapted to be locked thereto and having inclined surfaces, said intermediate member being formed of mating halves comprising portions which overlap.

8. In a work supporting block comprising a bottom member and an upper member, an intermediate member adapted to be locked thereto and having inclined surfaces, said intermediate member being formed of mating halves comprising portions which overlap, and which are adapted to be secured together by the extension of a clamping rod therethrough.

In testimony whereof I have signed my name to this specification.

BENNY M. SWANSON.
